(57) **CLAIM**

The ornamental design for an actuator head, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a first embodiment of the actuator head;

FIG. 2 is a front view thereof;

FIG. 3 is a left side view thereof;

FIG. 4 is a top view thereof;

FIG. 5 is a right side view thereof;

FIG. 6 is a rear view thereof;

FIG. 7 is a top front perspective view thereof;

FIG. 8 is a perspective view of a second embodiment of the actuator head;

FIG. 9 is a front view thereof;

FIG. 10 is a left side view thereof;

FIG. 11 is a top view thereof;

FIG. 12 is a right side view thereof;

FIG. 13 is a rear view thereof; and,

FIG. 14 is a top front perspective view thereof.

(Continued)

The part of the photographic renderings shown faded out
form no part of the claimed design.

1 Claim, 2 Drawing Sheets
